UNITED STATES PATENT OFFICE.

ALBERT STEFFIN, OF NEW BEDFORD, MASSACHUSETTS, ASSIGNOR TO PAIRPOINT CORPORATION, OF NEW BEDFORD, MASSACHUSETTS.

DESIGN FOR A GLASS VESSEL.

No. 39,982.

Specification for Design.

Patented May 11, 1909.

Application filed December 31, 1908. Serial No. 470,278. Term of patent 7 years.

To all whom it may concern:

Be it known that I, ALBERT STEFFIN, a citizen of the United States, residing at New Bedford, in the county of Bristol and State of Massachusetts, have invented a new, original, and ornamental Design for a Glass Vessel, of which the following is a specification, reference being had to the accompanying drawing, forming part thereof.

The figure is an elevation showing my new design.

The design resides in the ornamentation of the vessel as shown in the drawing consisting of three stems A, A, A, each of which extends upward and terminates in a daisy flower a, with leaves b, b, branching from the upright

stems below the terminating flowers. Where a portion of the daisy flower reaches the top rim of the vessel, the rim takes the shape of the outer edge of the flower, as shown at c. Intermediate leaves are introduced between the main stems of the daisy. The leaves are deeply formed so as to produce a prismatic effect.

What I claim as my invention is—

The ornamental design for a glass vessel as shown and described.

ALBERT STEFFIN.
